Primary Examiner — Deanna L Pratt(74) *Attorney, Agent, or Firm* — Rathe Lindenbaum LLP(57) **CLAIM**

We claim the ornamental design for a projected interface device, as shown and described.

DESCRIPTION

FIG. 1 is a top perspective view of a projected interface device;

FIG. 2 is a front view thereof;

FIG. 3 is a rear view thereof;

FIG. 4 is a right side view thereof;

FIG. 5 is a left side view thereof; and,

FIG. 6 is a top view thereof.

The dash-dash broken lines in the drawings are environmental lines which do not form part of the claimed design. The short dash-long dash lines are boundary lines which do not form part of the claimed design.
